US00D621730S

(12) **United States Design Patent**
Driver et al.

(10) **Patent No.:** US D621,730 S
(45) **Date of Patent:** ** Aug. 17, 2010

(54) **DIGITAL READ-OUT UNIT**

(75) Inventors: **John Driver**, Leicester (GB); **Tim Hatherley**, Leicester (GB)

(73) Assignee: **Newall Measurement Systems Limited**,
South Wigston, Leicestershire (GB)

(**) Term: **14 Years**

(21) Appl. No.: **29/344,072**

(22) Filed: **Sep. 23, 2009**

(30) **Foreign Application Priority Data**

Aug. 12, 2009 (EM) 00115926300010002

CLAIM

The ornamental designs of digital read-out unit, as shown and described.

DESCRIPTION

FIG. 1 is front perspective view of the free-standing digital read-out unit of our new design;

FIG. 2 is a rear perspective view of the free-standing digital read-out unit of our new design;

FIG. 3 is a front plan view of the free-standing digital read-out unit of our new design;

FIG. 4 is a rear plan view of the free-standing digital read-out unit of our new design;

FIG. 5 is a top plan view of the free-standing digital read-out unit of our new design;

FIG. 6 is a bottom plan view of the free-standing digital read-out unit of our new design;

FIG. 7 is a left side view of the free-standing digital read-out unit of our new design;

FIG. 8 is a right side view of the free-standing digital read-out unit of our new design;

FIG. 9 is front perspective view of the mountable digital read-out unit of our new design;

FIG. 10 is a rear perspective view of the mountable digital read-out unit of our new design;

FIG. 11 is a front plan view of the mountable digital read-out unit of our new design;

FIG. 12 is a rear plan view of the mountable digital read-out unit of our new design;

FIG. 13 is a top plan view of the mountable digital read-out unit of our new design;

FIG. 14 is a bottom plan view of the mountable digital read-out unit of our new design;

FIG. 15 is a left side view of the mountable digital read-out unit of our new design; and,

FIG. 16 is a right side view of the mountable digital read-out unit of our new design.
